FOREIGN PATENT DOCUMENTS

WO 2011097723 A1 8/2011

Primary Examiner — Jennifer L Watkins

(74) *Attorney, Agent, or Firm* — Norton Rose Fulbright Canada LLP; Alexandre Daoust

(57) CLAIM

The ornamental design for an orthotic foot brace, as shown and described.

DESCRIPTION

FIG. 1 is a perspective view of an orthotic foot brace showing my new design;

FIG. 2 is a left side elevation view thereof;

FIG. 3 is a front elevation view thereof;

FIG. 4 is a top plan view thereof;

FIG. 5 is a rear elevation view thereof;

FIG. 6 is a bottom view thereof; and,

FIG. 7 is a is another perspective view, in which the front portion is shown in a retracted state.

The broken lines are for the purpose of illustrating portions of an orthotic foot brace that form no part of the claim.

1 Claim, 7 Drawing Sheets
